UNITED STATES PATENT OFFICE.

VICTOR F. MAIDIHOFF AND MARGUERITE MAIDIHOFF, OF NEW YORK, N. Y.

DESIGN FOR A HAIR-PIN.

SPECIFICATION forming part of Design No. 28,411, dated March 29, 1898.

Application filed May 11, 1897. Serial No. 636,107. Term of patent 14 years.

To all whom it may concern:

Be it known that we, VICTOR F. MAIDIHOFF and MARGUERITE MAIDIHOFF, citizens of the United States, residing at New York city, in 5 the county and State of New York, have invented and produced a new and original Design for a Hair-Pin, of which the following is a specification, reference being had to the accompanying drawings, forming a part thereof, in which—

Figure 1 is a side elevation of a hair-pin embodying the features of our design, and Fig. 2 is a side elevation of a portion of one of the legs or members of the hair-pin drawn 5 on a larger scale.

The design consists in the form of the legs or members of a hair-pin, being a series of cylindrical surfaces 10 connected by similar

surfaces 11 of less diameter. The surfaces of less diameter, where they join those of greater diameter, are given a conical formation, as shown at 12 in the drawings. The general visual effect of the legs or members thus shaped is that of longitudinal undulating surfaces, composed of beads gradually 25 losing themselves in interposed and reduced cylindrical surfaces.

We claim—

The design for a hair-pin, substantially as herein shown and described.

VICTOR F. MAIDIHOFF.
MARGUERITE MAIDIHOFF.
